GUSTAV ANTON, OF PHILADELPHIA, PENNSYLVANIA.

Letters Patent No. 89,270, dated April 27, 1869.

HOLDER FOR CANDLES AND ORNAMENTS ON CHRISTMAS-TREES.

The Schedule referred to in these Letters Patent and making part of the same.

To all whom it may concern:

Be it known that I, GUSTAV ANTON, of the city of Philadelphia, and State of Pennsylvania, have invented a new and improved Holder for Candles and Ornaments on Christmas-Trees; and I do hereby declare the following to be a full and exact description of the same, reference being had to the accompanying drawings, and to the figures and letters of reference marked thereon.

The nature of my invention consists in combining with a candle-holder for Christmas-trees a series of receptacles for small flags, or other similar light ornaments.

Aside from the convenience which this arrangement of receptacles offers for distributing a variety of ornaments over a Christmas-tree, it has the great advantage of placing these adornments in a proximate position to the lights supported in the same holders, whereby the decorative effect of the ornaments is greatly increased.

In the following description of my invention, reference is had to the annexed drawings, in which similar letters of reference allude to like parts throughout the several views, and in which—

Figure 1 is a sectional elevation of my improved candle and ornament-holder, and

Figure 2 is a plan of the same.

The holder consists of three parts: the elastic socket A, for holding the candle; the dripping-cup B, and pin C, projecting through the bottom and serving as a means of attaching the whole to any part of the branches of the tree.

e e are the sockets provided in the cup B.

These sockets converge radially from the centre of the cup, and are shown in the drawing as supports for the staves of a series of small flags *ff*; but they may self-evidently be used for suspending any light ornaments of suitable description.

As a very cheap mode of forming these sockets *e e* in the cup B, I avail myself of the puckering tendency which the disk of metal has in being stamped up into the cup-shape, by drawing the surplus metal into a number of radial grooves. These grooves are afterward contracted at the bottom, and thus shaped into small sockets available for the described purpose.

It will be readily understood that these sockets, or any equivalent receptacles, may be formed or provided on the candle-holder in various ways for the same object, and although I have adopted the described cheap method of forming these receptacles, I do not limit myself to this particular arrangement of detail; nor do I claim as new and original the use of a pin or needle for securing the candle-holder in place; but

What I claim as my invention, and desire to secure by Letters Patent, is—

Combining with a candle-holder the described series of sockets, or their equivalents, substantially as and for the purpose set forth.

GUSTAV ANTON.
